COLLAPSIBLE DRESS FORM

Benjamin Wexler and Marvin C. Wexler,
Philadelphia, Pa.

Application July 19, 1950, Serial No. 174,750

14 Claims. (Cl. 223—68)

1

This invention relates generally to dress forms and more particularly to an improved construction of a readily expansible form which is adapted, when in its collapsed condition, to serve as a supporting hanger for a dress and, when in its fully expanded condition, to serve as a body-shaped form for displaying to best advantage the dress supported thereon.

Among the principal objects of the present invention is to provide a combination dress hanger and form which is so readily collapsible into the shape of a relatively flat unit that it may be conveniently carried by the salesman for use by him in the display of garments, such as dresses, offered for sale, the unit being readily expanded into shape to fill out the upper body portion of the dress and thus make unnecessary the time-consuming and often inconvenient practice of modeling the dress upon a living person or mannequin. In addition to such use of the form by traveling salesmen, it also may be conveniently employed in the shops displaying dresses and similar garments for sale, the units being there employed in their collapsed state as hangers for the dresses on display with each of them adapted for individual expansion to form an internal frame or bust form for each dress draped upon a hanger unit.

Further objects of the present invention, including the provision of a form of the character aforesaid which is simple in construction, inexpensive to manufacture and easy to use, will appear more fully hereinafter, it being understood that the present invention consists substantially in the combination, construction, location and relative arrangement of parts, all as described in detail hereinafter, as shown in the accompanying drawings and as finally pointed out in the appended claims.

In the accompanying drawings which are illustrative of a preferred embodiment of the invention:

Figure 1 is a perspective view showing the frame of the combination hanger and form expanded into bust-forming shape;

Figure 2 is a side elevational view showing the frame of Figure 1 in its collapsed or folded condition;

Figure 3 is a perspective view showing the expanded frame of Figure 1 encased within its fabric envelope;

Figure 4 is a vertical sectional view of the complete unit as shown in Figure 3;

Figure 5 is a side elevational view of the complete unit collapsed into condition adapting it for use as a dress hanger;

2

Figure 6 is a vertical section view of the unit as shown in Figure 5;

Figure 7 is a horizontal sectional view of the frame as taken on the line 7—7 of Figure 4;

Figure 8 is a perspective view like that of Figure 1 showing a modified construction of the combination hanger and form of the present invention;

Figure 9 is a side elevational view showing the frame of Figure 8 in its collapsed or folded condition;

Figure 10 is a vertical sectional view of the form as taken along the line 10—10 of Figure 8; and

Figure 11 is a horizontal sectional view as taken along the line 11—11 of Figure 10.

Referring now to the drawings and more particularly to Figures 1, 2 and 7 thereof, it will be observed that the combination hanger and form 20 of the present invention includes an internal frame unit 10 having a relatively rigid central main member 11 of inverted U-shape formed of suitably heavy wire stock, the opposed legs 12 and 13 of this central member being disposed in laterally spaced parallel relation with their upper ends interconnected by a top cross member 14. This latter member 14 is intermediately fitted with a short tubular guide element 15 arranged with its longitudinal bore substantially in axial coincidence with a line extending centrally between the leg portions 12 and 13 of the main member 11.

Slidably mounted upon the leg portions 12 and 13 of the central member 11 is a plurality of 35 vertically spaced frame members 16, 17 and 18, each of these latter being formed of a pair of arcuately-shaped elements hingedly connected together. Thus, the frame member 16 includes a pair of generally arcuately-shaped sections 16a—16b having their corresponding terminal ends hingedly connected, as at 16c—16c. The second frame member 17 similarly includes a pair of sections 17a—17b hingedly connected together as at 17c—17c, while the third frame member 18 includes a pair of sections 18a—18b hinged together as at 18c—18c.

It will be noted that the several frame members 16, 17 and 18 when fully extended as shown in Figures 1 and 4 are each of shape and perimetral size to respectively delineate the bust, waist and hip portions of the expanded form, it being further noted in this connection that the frame member 16b is of greater perimetral length than that of its associated frame member 55 16a to provide the increased frontal depth necessary to conform the frame 16 to the front bust

contour of the body. Also, to more closely simulate the natural shape of the body, the bust-forming frame section 16b is centrally indented, as at 16d.

The several bust, waist and hip-forming frames 16, 17 and 18 respectively include transversely extending central supporting rods 19, 20 and 21, the paired sections of each of said frames 16, 17 and 18 being hinged to the opposite extremities of said transverse rods. Each of these transverse rods 19, 20 and 21 is provided intermediate its opposite ends with a pair of laterally spaced tubular guide elements 22-23, the guide elements 22 being all axially aligned for slidable disposition upon the leg portion 12 of the main central member 11, while the guide elements 23 are all axially aligned for slidable disposition upon the opposite leg portion 13 of said central member 11.

The several cross rods 19, 20 and 21 are respectively secured, as at 24, 25 and 26, to an actuator rod or stem 27, the upper part of which slidably extends through the bore of the upper tubular guide element 15 and is terminally provided with a supporting hook 28 revoluble about the longitudinal axis of the actuator rod or stem 27.

Pivotedly connected to the rod 19 in the immediate vicinity of each of the tubular guide elements 22 and 23 is a pair of oppositely extending arms 29 and 30, the outer ends of which are respectively secured, as at 31 and 32, to the hingedly connected sections 16a and 16b of the bust-forming frame member 16. Operatively associated with each pair of these arms 29 and 30 is a pair of link arms 33 and 34, the inner ends of which latter are pivotally connected, as at 35, to a leg portion of the main central frame 11 while their outer ends are respectively pivotally connected, as at 36 and 37, to the arms 29 and 30.

The waist-forming frame 17 and the hip-forming frame 18 are each similarly provided with two sets of linkages as just described for the bust-forming frame, each set including a pair of arms 29a and 30a and a pair of link arms 33a and 34a for the waist-forming frame and a pair of arms 29b and 30b and a pair of link arms 33b and 34b for the hip-forming frame.

Finally, the upper transverse member 14 of the main central frame 11 of the unit is provided with a pair of laterally spaced shoulder plates 38-38, each of which is suitably mounted to permit it to be swung from its horizontal position as shown in Figures 1, 4 and 5 into a substantially vertical or vertically inclined position as shown in Figures 1 and 6.

The collapsible form of the present invention constructed as above described is completed by the provision of an enveloping jacket 39 of any suitable fabric or flexible material, this jacket being shaped generally in its bust, waist and hip regions to closely conform to and embrace the laterally extended bust, waist and hip-forming frames 16, 17 and 18 of the unit. The jacket 39 is fully enclosed on all sides thereof, its top or shoulder portion being provided with a neck opening 40 to permit the free upward projection therethrough of the supporting hook. The bottom edge of the jacket is secured, as by an in-turned hem 41, to the perimetral edge of the waist-forming frame 18.

Having in mind the foregoing construction, it will be apparent that when the actuator stem or rod 27 is shifted vertically upward relatively to the central U-shaped frame 11, the several transversely extending rods 19, 20 and 21 will be shifted upwardly into their positions shown in Figure 1,

this movement of the several rods 19, 20 and 21 being along a rectilinear path determined by the guide elements 22-23 respectively movable on the relatively fixed frame members 12 and 13.

As these rods 19, 20 and 21 are shifted upwardly the two sets of linkages operatively associated with each of these rods operate to cause the arms 29-30, 29a-30a and 29b-30b to shift into longitudinally extended relation with the result that the hinged sections of the several bust, waist and hip-forming frames are correspondingly shifted into substantially horizontally extended relation, as shown in Figure 1.

The several pivots of each linkage set are relatively so spaced as to permit the transversely extending rods 19, 20 and 21 to shift upwardly from a position substantially below to a position immediately above the horizontal planes of the laterally extended frame sections, the leverage arrangement being that of a toggle which is operative to lock the several bust, waist and hip-forming frames in their fully opened or expanded condition when the actuator rod 27 is in its fully raised position. If desired, any suitable auxiliary means (not shown) may be employed to lock the actuator in its fully raised or fully lowered position relatively to the frame member 11, a preferred means for such auxiliary locking being the conventional umbrella type spring-pressed latch which may be fitted in the actuator rod 27 for passage upwardly therewith through the tubular guide 15 for latching engagement with the upper end of said guide to prevent unintentional retraction of the actuator rod relatively to said guide.

In use of the device of the present invention, the dress or other garment to be displayed upon the combination form and hanger may be draped thereon while the unit is in its collapsed form, as shown in Figures 5 and 6, in which case the unit serves primarily as a hanger for the freely suspended dress. The collapsed unit with the dress so suspended thereon may be conveniently packed in a traveling case, or it may be hung upon a rack of the type conventionally employed in dress shops. When it is desired to display the dress as it would appear when it is worn upon the body, the actuator rod 27 is shifted upwardly relatively to the frame 11 as just above described, to expand the unit into body form and so fill out the dress suspended thereon. The prospective purchaser of the dress is thus enabled to visualize the dress as it would appear when worn, thereby avoiding the necessity of modeling the dress upon a living person or form.

Figures 8 to 11, inclusive, show a modified construction of the combination form and hanger wherein the several bust, waist and hip-forming frame members are formed of flat metal stock rather than of wire rod as in the form previously described. Thus, the bust-forming frame member is formed of a pair of suitably shaped flat metal elements 40-40 hinged together as at 41-41, while the waist-forming frame member is formed of a pair of flat metal elements 42-42 hinged together as at 43-43 and the hip-forming frame member is formed of a pair of flat metal elements 44-44 hinged together as at 45-45.

The hinge pins 46 of the several vertically spaced collapsible frame members, at each side of the combination form and hanger, project through and are supported by the vertically extending side legs 47-47 of a relatively rigid main frame member 48 of inverted U-shape, this latter member being also formed of flat metal stock rather than wire rod. The side legs 47-47 of

5

the main frame member 48 are respectively shaped to conform generally to body shape, the upper ends of these side legs being interconnected by the transversely extending element 49 to the central point of which is rotatably or otherwise secured a suitable hanger hook 50.

As in the previously described form of the invention, the collapsible bust, waist and hip-forming frame members are adapted to be expanded into horizontally extending condition as shown in Figures 8 and 10 or collapsed into folded condition as shown in Figure 9, in which latter condition the hinged elements of each such frame member are respectively folded upwardly about the opposed hinge pins 46-46 which secure the several collapsible frame members to the main supporting frame 48.

To effect the expansion and collapse of the vertically spaced collapsible frame members, an actuating mechanism may be employed, as shown in the modified form of construction, comprising a vertically shiftable actuator rod 51 connected through the medium of an exceedingly simple linkage system to the several members. The actuator rod 51 is guided in its vertical travel by projecting it through suitable vertically aligned guide openings 52 and 53 formed respectively in vertically spaced cross bars 54-54 interconnecting the side legs 47-47 of the main supporting frame 48, these cross bars serving additionally to reinforce and rigidify the frame.

The upper end of the actuator rod 51 is suitably bent, as at 55, to provide a convenient hand hold for raising and lowering the same relatively to the main frame 48 and is further offset, as at 56, to provide a stop engageable with the upper cross bars 54 to limit downward movement of the actuator rod.

The paired elements of each collapsible frame member are respectively provided with a transversely extending rod interconnecting the opposite sides of each hinged element. Thus, the hinged elements 40-40 are respectively provided with the cross rods 56-56, the elements 42-42 with the rods 57-57 and the elements 44-44 with the rods 58-58. These cross rods not only strengthen and reinforce the elements of which they form parts, but also, as most clearly appears in Figures 8 and 10, they provide a simple means for interconnecting each group of the vertically spaced hinged elements for conjoint raising and lowering about their supporting pivot pins. Thus, the several elements 40, 42 and 44, to each side of the main frame member 48, are interconnected by vertically extending tie rods 59 and 60, the tie rod 59 interconnecting the mid-points of the vertically spaced cross-rods 56 and 57, while the tie-rod 60 interconnects the midpoints of the vertically spaced cross rods 57 and 58. The opposite ends of the tie rods 59 and 60 are enlarged and apertured to permit free projection of the cross rods therethrough and provide for a hinging action at each point of connection between the tie rods and the cross rods.

Fixed to the actuator rod 50 is an inverted clip 61 which carries a pair of pins 62-62 respectively disposed to either side of the rod 50 and extending parallel to the several cross rods 56, 57 and 58. A pair of links 63-63 respectively interconnect the pins 62-62 to the uppermost pair of the cross rods 56-56 to complete the linkage system, it being apparent that upon raising the actuator rod 50 relatively to the main frame 48, the linkage system operates to simultaneously collapse the several bust, waist and hip-forming frame 75

6

members into their folded condition shown in Figure 9. When it is desired to expand these frame members, as shown in Figure 8, it is only necessary to depress the actuator rod relatively to the main supporting frame.

As in the case of the previously described modification of the invention, the main frame 48 may be provided with shoulder plates 64-64, while the assembly as a unit may be encased within an 10 enveloping jacket similar to that designated 39 in Figures 3 and 4.

It will be understood, of course, that the present invention is susceptible of various changes and modifications which may be made from time to time without departing from the general principles or real spirit thereof, and it is accordingly intended to claim the same broadly, as well as specifically, as indicated in the appended claims.

What is claimed as new and useful is:

1. A collapsible form of the character described comprising a central main supporting frame having a pair of laterally spaced, parallel members, a plurality of body-forming frames each including a rod extending transversely of said laterally spaced members of the supporting frame and a pair of relatively foldable sections hingedly connected to said rod, said transversely extending rods being disposed in vertically spaced parallel relation and being guided on said laterally spaced members of the central supporting frame for vertical movement thereon, and toggle means interconnecting each pair of foldable body-forming sections with their associated transversely extending rod and with said laterally spaced members, said toggle means being operative to permit each of the paired foldable sections to assume either a relatively folded position or a relatively extended position.

2. A collapsible form of the character described comprising a central main supporting frame having a pair of laterally spaced, parallel members, a plurality of body-forming frames each including a rod extending transversely of said laterally spaced members of the supporting frame and a pair of relatively foldable sections hingedly connected to said rod, said transversely extending rods being disposed in vertically spaced parallel relation and being guided on said laterally spaced members of the central supporting frame for vertical movement thereon, toggle means interconnecting each pair of foldable body-forming sections with their associated transversely extending rod and with said laterally spaced members, said toggle means being operative to permit each of the paired foldable sections to assume either a relatively folded position or a relatively extended position, and a member extending longitudinally of said supporting frame and connected to each of said vertically spaced transversely extending rods for vertically moving the same in unison relative to said supporting frame to effect simultaneous collapse of the body-forming frames into relatively folded condition or expansion thereof into relatively extended condition.

3. A collapsible form of the character described comprising a plurality of vertically spaced body-forming frames each including a pair of relatively foldable sections, a transversely extending rod for each body-forming frame to the opposite ends of which each pair of said foldable sections are hingedly secured, a main central support for said body-forming frames, said support having a pair of laterally spaced members for vertical movement thereon of said

transversely extending rods of said body-forming frames, toggle linkages interconnecting each pair of relatively foldable sections of a body-forming frame with their associated transversely extending rod and with said laterally spaced members, and a rigid member extending longitudinally of said supporting frame and connected to the transversely extending rods of the several body-forming frames for simultaneously actuating said toggle linkages to collapse or expand said frames as desired.

4. In a collapsible form of the character defined in claim 3 wherein said paired foldable sections of said body-forming frames are in the form of wire members arcuately shaped to provide said frames, when expanded into extended relation, with perimetral outlines respectively in conformity with the bust, waist and hip portions of the body.

5. In a collapsible form of the character defined in claim 3 wherein said body-forming frames, when expanded into body-forming shape, are respectively of perimetral outlines generally conforming to the bust, waist and hip portions of the body, and wherein is included a jacket of flexible material enveloping said form and adapted to be expanded into body shape upon outward extension of the relatively foldable sections of the several body forming frames.

6. A collapsible form of the character described comprising a main supporting frame having a pair of laterally spaced, depending side elements, a plurality of foldable body-forming frames each including a pair of members hinged together and to said main supporting frame, and longitudinally extending rigid means interconnecting each pair of said foldable body-forming members, said rigid means being operable to simultaneously cause each foldable body-forming member to assume either a relatively folded position or a relatively extended position.

7. A collapsible form of the character described comprising a main supporting frame having a pair of laterally spaced, depending side elements, a plurality of foldable body-forming frames each including a pair of members hinged together at laterally spaced points respectively adjoining the depending side elements of said main supporting frame, link means interconnecting the corresponding members of the several body-forming frames for conjoint collapse and expansion of the latter, and means longitudinally shiftable relative to said supporting frame and associated with said link means for actuating the same in unison to effect simultaneous collapse of the body forming frames into relatively folded condition or expansion thereof into relatively extended condition.

8. In a collapsible form of the character defined in claim 7 wherein said paired foldable sections of said body-forming frames are in the form of members arcuately shaped to provide said frames, when expanded into extended relation, with perimetral outlines respectively in conformity with the bust, waist and hip portions of the body.

9. In a collapsible form of the character defined in claim 7 wherein said body-forming frames, when expanded into body-forming shape, are respectively of perimetral outlines generally conforming to the bust, waist and hip portions of the body, and wherein is included a jacket of flexible material enveloping said form and adapted to be expanded into body shape upon

outward extension of the relatively foldable sections of the several body-forming frames.

10. A collapsible form of the character described comprising a main supporting frame of inverted U-shape having a pair of laterally spaced, depending side elements, a plurality of vertically spaced foldable body-forming frames each including a pair of members hinged to each other and to the side elements of said main frame, rigid link means interconnecting the vertically spaced body-forming frame members hinged to said frame, and an actuator rod vertically shiftable relative to said supporting frame and operatively associated with said interconnecting rigid link means for effecting conjoint collapse or expansion of said foldable body-forming frames in response to said shifting movement.

11. A collapsible form of the character described comprising a main supporting frame of inverted U-shape having a pair of laterally spaced, depending side elements, a plurality of vertically spaced foldable body-forming frames each including a pair of members hinged to each other and to the side elements of said main frame, rigid link means interconnecting the vertically spaced body-forming frame members hinged to said frame, and an actuator rod vertically shiftable relative to said supporting frame and operatively associated with said interconnecting rigid link means for effecting conjoint collapse or expansion of said foldable body-forming frames in response to vertical shifting of said actuator rod, said actuator rod being guided for rectilinear movement along a vertically extending line located centrally between and substantially in the common plane of the side elements of said main frame.

12. A collapsible form of the character described comprising a main supporting frame having a pair of laterally spaced, side elements, a plurality of vertically spaced, foldable body-forming frames each including a pair of members hinged to each other and to the side elements of said main frame, rigid link means between the corresponding vertically spaced members of the several body-forming frames, and means vertically shiftable relative to said supporting frame and operatively associated with said rigid link means for effecting conjoint collapse or expansion of said foldable body-forming frames in response to said shifting movement.

13. In a collapsible form as defined in claim 11 wherein said interconnecting means include horizontally extending rods for each body-forming frame member and connector rods extending between and interconnecting said horizontally extending rods, and wherein said vertically shiftable actuator rod is linked to said connector rods for conjoint raising and lowering of the latter to simultaneously effect movement of the paired members of said body-forming frames about their hinged axes inwardly and outwardly with respect to said main supporting frame.

14. A collapsible form of the character described comprising a main supporting frame having a pair of laterally spaced, depending side elements, a plurality of foldable body-forming frames each including a pair of members hinged at spaced points respectively adjoining the depending side elements of said main supporting frame, means longitudinally shiftable relative to said supporting frame, and link means pivotally connected with the several body-forming frames and operably associated with said longitudinally shiftable means for actuation of said body-form-

ing frames in unison to effect simultaneous collapse thereof into relatively folded condition or expansion thereof into relatively extended condition in response to movement of said longitudinally shiftable means.
